J. E. S. RUSSELL

LAUNDRY CARRIER

Filed April 21, 1926

Inventor
Jesse E.S. Russell
by Attorney

UNITED STATES PATENT OFFICE.

JESSE E. S. RUSSELL, OF LOS ANGELES, CALIFORNIA.

LAUNDRY CARRIER.

Application filed April 21, 1926. Serial No. 103,492.

This invention has to do with a laundry carrier and it is an object of the invention to provide a device to aid in and simplify the handling of bundles or parcels of laundry, or the like.

Many laundries at the present time employ a system of handling clothes known as the key tag system, in accordance with which system the clothes belonging to a customer are placed in several net bags each carrying a plate bearing a given number and having an opening of a certain configuration. Bags containing the clothes of several customers are washed in a lot, after which the bags are sorted out by means of the numbers on the plates and by applying the plates to pins or hooks of certain configurations, there being one hook only that will receive plates of a given number. For example, there is one hook only of a configuration which will receive or fit the openings in the plates attached to the bags containing the clothes of one customer.

It is an object of this invention to provide a carrier including a plurality of hooks or pins to receive bundles or bags of the laundry so that the bags can be sorted onto the carrier at one location and the carrier moved to another location where the sorted bags can be removed and the laundry from each group of bags wrapped or otherwise handled.

It is another object of this invention to provide a carrier of the character mentioned which is of simple, inexpensive construction and is easy to operate.

A further object of the invention is to provide a carrier of the character mentioned which can be installed in a comparatively small space.

The various objects and features of my present invention will be best and more fully understood from the following detailed description of a typical preferred form and application of the invention throughout which description reference is had to the accompanying drawings in which:

Fig. 1 is a longitudinal sectional view of the apparatus provided by this invention;

Fig. 2 is a plan view of the apparatus, being a view taken as indicated by line 2—2 on Fig. 1;

Fig. 3 is an enlarged detail view taken as indicated by line 3—3 on Fig. 2;

Fig. 4 is a view taken as indicated by line 4—4 on Fig. 3;

Fig. 5 is an enlarged detail section taken as indicated by line 5—5 on Fig. 1;

Fig. 6 is an enlarged detail section taken as indicated by line 6—6 on Fig. 2;

Fig. 7 is an enlarged detail section taken as indicated by line 7—7 on Fig. 2 and

Fig. 8 is a view taken as indicated by line 8—8 on Fig. 1.

The device provided by this invention includes, generally, what I will term a trackway 10, carriers 11 supported by and operating on the trackway, stop means for the carriers, and various other parts the details and functions of which will be hereinafter described.

In accordance with the broader principles of my invention the trackway 10 may be constructed in various manners and the various parts thereof may be arranged or related in several different ways. I have in this case set forth only one typical arrangement or construction of trackway but do not wish the invention understood as thereby limited or restricted. The trackway as shown in the drawings includes, generally, a pair of delivery rails 14, a pair of return rails 15, curved extensions at the ends of the rails 14 and 15 whereby the carriers hereinafter described may be passed between the ends of the rails 14 and 15. In the arrangement shown the delivery rails 14 are arranged above the return rails 15 and suitable standards 17 are provided to support the rails. The delivery rails 14 are pitched or inclined downwardly so that their discharge ends are lower than their receiving ends, and the return rails 15 are pitched or inclined so that their receiving ends are higher than their discharge ends.

The delivery and return rails are of course oppositely related or pitched so that the high ends of the return rails are opposite or under the low ends of the delivery rails. The standards 17 are arranged outside the pairs of rails so that the space between the rails is clear to carry the carriers 11 as will be hereinafter described. In the particular arrangement shown the rails are supported at each end by a standard 17 and at a point intermediate their length by another standard 17. The standards may be suitable frame structures formed of angle iron, or the like, provided with horizontally disposed brackets 20 which extend under and support the rails. In the form of construction shown in the drawings the delivery rails

14 are provided at their lower ends with downwardly extending semi-circular rail extensions 21, while the return rails 15 are provided at their upper ends with upwardly extending semi-circular rail extensions 22 which are of greater radius than the extensions 21. The extensions 21 and 22 are related so that the extension 22 extends around or outside the extension 21 in spaced relation thereto, the space between the extensions corresponding to the diameter of the mounting wheels which are hereinafter described. The delivery rails 14 are provided at their upper ends with downwardly extending semi-circular rail extensions 23 similar to the extensions 21, while the return rails 15 are provided at their lower ends with upwardly extending semi-circular extensions 24 similar to the extensions 22. The curved extensions 23 and 24 are arranged in spaced relation similar to the extensions 21 and 22 to carry the mounting wheels as hereinafter described.

In practice the device may be provided with various numbers of carriers 11. The carriers extend between or are carried by the rails of the trackway above described. I have, for sake of example, shown the device provided with several carriers 11 and have shown one of the carriers at the upper end 30 of the delivery rails, at which point carriers are loaded, and have shown the other carrier at the lower end of the delivery rails, at which point the carriers are unloaded.

Each carrier may comprise a comparatively long beam having a plurality of pins or hooks 30 projecting from it. The ends of the beam 31 are supported on the rails through wheels 32. In the preferred arrangement each end of the beam 31 is supported 40 through a pair of wheels 32 so that the beam is effectively supported against turning or rotation. In the construction shown in the drawings each pair of wheels is mounted on a plate 33 attached to the end of the beam 31 through a suitable angle iron 34, or the like. In practice it is desirable to connect one of the wheels 32 at one end of the beam with the corresponding wheel at the other end of the beam so that these two wheels 50 rotate together or at the same speed. This interconnection may be made by fixing one of the wheels 32 at one end of the beam and the corresponding wheel at the other end of the beam on a shaft 36 which extends between the plates 33 parallel with the beam 31. The shaft may be carried in bearings 60 mounted on the beam. This construction is employed to prevent binding of the carriers or wheels 32. The wheels 32 are provided with flanges 40 by which they are effectively held on the rails. Bumpers 61 may be provided on the carriers as shown in the drawings.

Stops 44 are carried on pivot pins 45 at 65 the upper ends of the delivery rails to catch

and hold the ends of the beams 31 upon the beams being moved to loading position at the upper ends of the delivery rails 14. The stops 44 may be in the form of hooks which normally hang in position to engage the end portions of the beams as the beams are moved to the loading position. A beam or carrier held by the stops 44 may be released by lifting the stops up out of engagement with the end portions of the beam. 75

Spring supported stops 46 are provided at the lower ends of the delivery rails 14 to catch and hold the carriers in the unloading position or at the lower ends of the rails 14. The stops 46 may be in the form of hooks 80 slidably held by bolts 47. Springs 48 may be provided in connection with the hook stops 46 so that they are extended and absorb the shock when the hooks are engaged by the carriers. The stops 46 may be normally held up by leaf springs 49 so that they are in position to catch the end portions of the beams of the carriers. The springs 49 allow the stops to be depressed to release the carriers when it is desired to move the carriers 85 from the delivery rails to the return rails.

Stops 70 may be provided at suitable points in connection with the return rails to the carriers in case it is not desired to allow the carriers to run freely to the lower ends of the return rails when released from the unloading position.

One of the return rails may be constructed with a hinged section 15^a which can be swung to one side to allow a truck, or the like, carrying bags of clothes to be moved into position between the rails where the bags can be conveniently reached to apply them to the pins on the carrier.

In operation the bags of laundry are applied or sorted onto the key hooks 30 while the carrier is in the loading position at the upper end of the pair of delivery rails 14. When the hooks are loaded, that is when all of the bags have been sorted onto the hooks, 110 the catches or stops 44 are released allowing the carrier to roll down along the rails 14 until they engage or are caught by the stops 46. The bags of clothes are removed from the hooks 30 while the carrier is in the unloading position held by the stops 46. When the carrier is completely unloaded the stops 46 are depressed releasing the carrier, so that its supporting wheels pass onto and around the rail extensions 21 and 22, by which operation the carrier is transferred from the delivery rails to the return rails. The return rails carry the carrier to the rail extensions 23 and 24. When the carrier is again required for use the operator moves it from the lower end of the pair of return rails to the receiving end of the pair of delivery rails during which operation the wheels 32 pass along and between the rail extensions 23 and 24 and are thereby trans- 115 120 125 130

ferred from the return rails to the delivery rails. It will be apparent from the foregoing description how several carriers may be kept in operation and how the device 5 simplifies the handling and sorting of the bags of laundry.

Having described only a typical preferred form of my invention I do not wish to limit myself to the specific details set forth, but 10 I wish to reserve to myself any changes or variations that may appear to those skilled in the art, or may fall within the scope of the following claims:

Having described my invention I claim:

1. Laundry handling apparatus including 15 a carrier having a beam, key, projections on the beam to receive and hold bags of laundry, and a trackway supporting the beam so that it is movable between a loading position and an unloading position.

2. A carrier of the character described 20 including a beam, projections on the beam to hold laundry, wheels at the ends of the beam, means connecting the wheels at the two ends of the beams so that they operate together, and a trackway supporting the beam through the wheels so that the beam is movable between a loading position and an unloading position.

3. A carrier of the character described 25 including a beam, projections on the beam to hold laundry, two spaced wheels at each end of the beam, means operatively connecting one of the wheels at one end of the beam with one of the wheels at the other end of the beam, and a trackway supporting the beam through the wheels so that it is movable between a loading and an unloading position.

4. A carrier of the character described 30 including a beam, projections on the beam to hold laundry, wheels at the ends of the beam, and a trackway supporting the beam through the wheels so that the beam is movable between a loading position and an unloading position, the trackway including a pair of delivery rails for carrying the wheels from the loading position to the unloading position and a pair of return rails for carrying the wheels from the unloading position to the loading position.

5. A carrier of the character described 35 including a beam, projections on the beam to hold laundry, wheels at the ends of the beam, and a trackway supporting the beam through the wheels so that the beam is movable between a loading position and an unloading position, the trackway including a pair of delivery rails for carrying the wheels from the loading position to the unloading position and a pair of return rails arranged below the delivery rails for carrying the wheels from the unloading position to the loading position.

6. A carrier of the character described in-

cluding a beam, projections on the beam to hold laundry, wheels at the ends of the beam, and a trackway supporting the beam through the wheels so that the beam is movable between a loading position and an unloading position, the trackway including a pair of delivery rails and a pair of return rails one above the other, and extensions on the ends of said rails for carrying the wheels from one pair of rails to the other. 75

7. A carrier of the character described including a beam, projections on the beam to hold laundry, wheels at the ends of the beam, and a trackway supporting the beam through the wheels so that the beam is movable between a loading position and an unloading position, the trackway including a pair of delivery rails and a pair of return rails one above the other, and curved extensions on the ends of said rails for carrying the wheels 80 from one pair of rails to the other. 85

8. A carrier of the character described including a beam, projections on the beam to hold laundry, wheels at the ends of the beam, and a trackway supporting the beam through 90 the wheels so that the beam is movable between a loading position and an unloading position, the trackway including a pair of delivery rails and a pair of return rails one above the other, and overlapping curved extensions on the ends of said rails for carrying the wheels from one pair of rails to the other. 95

9. A carrier of the character described including a beam, projections on the beam to hold laundry, wheels at the ends of the beam, a shaft connecting the wheels at the two ends of the beam so that they operate together, and a trackway supporting the beam through the wheels so that the beam is movable between a loading position and an unloading position. 100

10. A carrier of the character described including a beam, projections on the beam to hold laundry, wheels at the ends of the beam, a trackway supporting the beam through the wheels so that the beam is movable between a loading position and an unloading position, and releasable stop means for holding the carrier in one of said positions. 110

11. A carrier of the character described including a beam, projections on the beam to hold laundry, wheels at the ends of the beam, a trackway supporting the beam through the wheels so that the beam is movable between a loading position and an unloading position, and releasable yielding stop means for catching and holding the carrier in the unloading position. 120

12. In laundry handling apparatus a carrier, and a trackway for the carrier including delivery rails for carrying the carrier from a loading position to an unloading position, and return rails for carrying the 130

- carrier from the unloading position to the loading position.
13. In laundry handling apparatus a laundry carrier, and a trackway for the carrier including a pair of delivery rails and a pair of return rails, the two pairs of rails being spaced apart, and rail extensions at both ends of both pairs of rails for carrying the carrier between the two pairs of rails.
14. In laundry handling apparatus a laundry carrier, and a trackway for the carrier including delivery rails for carrying the carrier from a loading position to an unloading position, and return rails for carrying the carrier from the unloading position to the loading position, one of the rails having a portion movable into and out of operating position to allow passage of objects into position between the rails.
15. In laundry handling apparatus a carrier, and a trackway for the carrier includ-

ing delivery rails for carrying the carrier from a loading position to an unloading position, and return rails for carrying the carrier from the unloading position to the loading position, one of the rails having a hinged portion movable into and out of operating position to allow passage of objects into position between the rails.

16. A carrier of the character described including a beam to hold laundry, wheels at the ends of the beam, a trackway supporting the beam through the wheels so that the beam is movable between a loading position and an unloading position, and releasable stop means for the carrier at both ends of the trackway.

In witness that I claim the foregoing I have hereunto subscribed my name this 14th day of April, 1926.

JESSE E. S. RUSSELL.
